DESIGN FOR A BROOCH OR SIMILAR ARTICLE

Jack Silson, New York, N. Y.

Application October 6, 1941, Serial No. 103,652

Term of patent 3½ years

To all whom it may concern:

Be it known that I, Jack Silson, a subject of the King of Great Britain, residing in New York city, county of New York, and State of New York, have invented a new, original, and ornamental Design for a Brooch or Similar Article, of which the following is a specification, reference being had to the accompanying drawing, forming part thereof.

Fig. 1 is a plan view of a brooch or similar article showing my new design.

Fig. 2 is an edge view thereof.

I claim:

The ornamental design for a brooch or similar article, substantially as shown.

JACK SILSON.
